APPARATUS FOR HANDLING LIQUEFIED
GASES

Rossell W. Thomas and Frederick J. Harlow,
Detroit, Mich., assignors to Phillips Petroleum
Company, Bartlesville, Okla., a corporation of
Delaware

Application September 25, 1931, Serial No. 565,154

6 Claims. (Cl. 158—53)

This invention relates to a method of and apparatus for vaporizing volatile liquids and particularly liquefied petroleum gases.

One of the objects of the present invention is to provide an apparatus wherein the pressure of the liquefied gas is reduced before the same enters that portion of the apparatus in which the latent heat of vaporization is restored to the liquefied gas, and to control the feed so as to maintain substantially constant the pressure at that point, regardless of the temperature of the gas. Certain safety appliances are incorporated in the apparatus and also an automatic device for controlling the delivery of the gas to the consuming apparatus after the same has been changed from a liquid to a gas. The invention also contemplates the automatic supply of the heating medium used, to supply the latent heat of vaporizing, by using the pressure or temperature of the gas which is passed through the heat exchange unit of the apparatus. Further provision is made for the manual operation of the apparatus when, for any reason, the automatic elements of the apparatus cease to function.

It has been found desirable to liquefy certain of the volatile petroleum gases used for commercial purposes so that the same can be distributed to the trade for consumption in an economical manner. For example, to liquefy these gases by the compression and cooling method, the following steps must be taken. The gas is first compressed slightly above the vapor pressure of the liquid at the temperature of the cooling medium, which is to be used in cooling the compressed gas. After compression, the gas is subjected to contact with the cooling medium by means of a tube condenser or the like, and the heat of compression removed from the compressed gas. However, at this point, the gas is not condensed or liquefied until an additional amount of heat is removed, this additional amount being the latent heat of vaporization or the heat of state of change. After this amount of heat has been removed, the compressed gas will condense and shrink in volume.

To show the many problems involved, all of which must be taken into consideration in constructing a device of this kind, we will show certain specifications of one of the petroleum gases, i. e. commercial butane, which has proven most satisfactory in a machine of this kind.

Commercial butane gas at 60° F. will shrink in volume so that 1 cu. ft. of liquid will contain 240 cu. ft. of gas at the same temperature. As 55 1 cu. ft. of butane gas contains 3200 B. t. u.'s, it

will be seen that a cu. ft. of the same liquefied gas contains 768,000 B. t. u.'s, which is an enormous concentration of heat. For this reason, it is usually impractical to utilize the liquefied gas because of the amount of heat contained within the same. The greatest utilization of this gas demands that the liquefied gas be restored to its natural state, i. e. a gas. The vapor pressure of the same commercial gas at 70° F. is about 33 pounds per sq. in. which pressure increases until 10 at 130° F. the pressure is about 110 pounds per sq. in. This change in vapor pressure, with temperature change, must also be taken into consideration in a vaporizing device, so that regardless of the temperature of the atmosphere, the 15 vaporizer will function in a uniform way.

To vaporize the liquefied gas, steps must be taken which are the reverse of the liquefying process pointed out above. This invention, therefore, contemplates a method and/or apparatus 20 for reconverting the liquefied gas to a vapor state, together with certain automatic controls for the different parts of the apparatus, all of which will be described more fully hereinafter.

Referring to the accompanying drawing, the 25 figure represents a diagrammatic elevation of an apparatus embodying our invention, certain parts of which are shown in section.

The following description, charted by arrows, shows the normal course of the gas in a liquid 30 state until the same arrives at the place of consumption as a gas. In the arrangement shown, gas enters the pipe A in a liquid state by vapor pressure from a source of supply, usually a storage tank. The normal path of the gas from the 35 storage tank is through the pipes A, B, C, D and strainer 3 to the heat exchange unit P, wherein the liquid gas is finally returned to a true gas. In the unit P, the expanded liquid or vapor, which has not yet become a true gas because the latent 40 heat of vaporization has not been supplied, becomes a true gas. From the heat exchange unit through which it is preferably conducted around a series of pipes 12, to be treated by a heating medium, the true gas passes through the line J 45 to the safety trap 13 which will hereafter be described. From the safety trap, the gas is conducted through the lines K, W and G, and through the strainer 24 into the gas regulator 17. After the gas leaves the regulator, it traverses the remainder of the line G, lines V, T and S to the place of consumption. It takes this course because the valves 8, 9, 10, 11, 18 and 19 are closed, and 1, 2, 4, 21, 7, 14, 22 and 23 are 50 open. 55

Having described the course of the liquid and gas through the apparatus, we will take up and describe the automatic devices which control and distribute the gas throughout its course through the apparatus. Connecting the lines B and C is the expansion valve 4, of any standard make, the position of which is controlled by a diaphragm 5 of the weight and lever or spring control type. The valve 4 functions as follows:—

- 10 The volatile liquid arrives at the intake of valve 4 by virtue of the vapor pressure of the liquid in the storage tank at a pressure higher than that desired in the heat exchange unit P. In the body of the valve 4, there is a valve head attached to 15 the lower end of a valve stem; the upper end of the stem being connected to the center of the diaphragm 5 in the diaphragm chamber, which is part of the valve proper. As liquid gas passes through the body of the valve 4 from B to C when 20 the valves 7, 8, 9, 10 and 11 in the lines D, H, I, E and F respectively are closed, there will be a back pressure built up on the line C, part of lines D, I, E and the whole of O, all of these lines being 25 beyond the expansion valve 4. This pressure will correspond to the vapor pressure in the storage tank, minus the pressure required to conduct the gas through these lines. Now, if the weight 4^a is removed from the lever arm 4^b, pivoted at 30 intermediate the ends thereof and forming part 30 of the valve mechanism 4, the pressure on the top side of the diaphragm 5 will cause the stem to force downwards thereby closing valve 4. If the weight 4^a is returned to the lever arm 4^b, it will be readily seen that by balancing the correct 35 pressure on the top side of the diaphragm 5, any desired pressure in the closed system beyond the seat of the valve 4 can be obtained. It will be seen that any variations in demand on the heat exchange unit P will also vary the pressure in the 40 lines D, C, part of lines I and E, and all of O. Finally, through line O any variation in back pressure will be transmitted to the top of the diaphragm which is now counter-balanced by the weight on the lever arm and any drop in 45 pressure in line O will cause the valve to open as the balancing pressure to the weight has been lessened. The valve will then remain open until the pressure in line O again builds up to a pressure which will close the valve to a point consistent 50 with the discharge pressure of the valve 4. The control of the liquid passing through the valve 4 is therefore automatic and maintained by the demand of the equipment beyond the valve 4. In handling commercial butane, the 55 pressure on the discharge side of valve 4 is usually balanced at about 5 lbs., which means that the expanded fluid enters the heat exchange unit P at about 5 lbs. pressure. Not only does the valve 4 feed fluid to the heat exchange unit so as to 60 maintain constant the feed as governed by conditions around the heat exchange unit, but it also reduces the pressure produced by the source of supply to a proper pressure so that the liquid can be properly treated. The pressure of the liquid as it reaches the valve 4 is considerably 65 over 5 lbs.

The heat exchange unit P is of the multi-tubular type and comprises a series of pipes 12 around which the gas flows so as to increase the 70 area of the gas exposed to the effect of the heating medium. The heating medium which enters the heat exchange unit through the control valve 16 or 16^a, depending on which direction it is passed through the exchanger, can be either hot 75 water, steam, hot oil or the like. Electrical re-

sistance elements can be used to supply the latent heat of vaporization, in which case they would be used instead of the tubes 12, and might be controlled by a rheostat instead of the valve 16 or 16^a, which controls the flow of the heating medium to the heat exchange unit. The output of the rheostat would be governed by a thermostatic element 15 in the pipe J. Provision has been made to permit draining the gas chamber of the heat exchange unit P through the drain 30, which is located in the lowest point of this unit. Through the drain 32, the heat supplying medium can be drained away from the pipes when it is desired to eliminate all possibility of the heating medium freezing around the pipes, when the apparatus 15 is closed down in cold weather.

In the line J between the valve 14 and the safety trap 13, is the automatic control device 15 for regulating by temperature the supply of the heating medium to supply the latent heat of vaporization. This control is through the valve 16 in the line carrying the heating medium to the heat exchange unit. It will be thus seen that the temperature in the line J controls the amount of the heating medium which enters the heat exchange unit P, in which the liquefied gas is changed into a true gas. The thermostatic control 15 is not absolutely essential to the successful operation of the apparatus, and, when employed, may be of any suitable and desirable conventional or standard construction. A thermostatic control device suitable for our purposes is disclosed in U. S. Patent No. 1,278,749 dated September 10, 1918.

The safety trap 13 is of any approved float type liquid valve control which may function as follows:—The single seated unbalanced valve 100 operated by the float 101, closes in the direction of gas or liquid flow when the liquid in the float chamber rises to a point which is below the bottom of the line K, so that no liquid will enter the line K. This safety trap is not an absolutely essential part of the apparatus, and may or may not be used. When used, it may be of any suitable and desirable conventional or standard construction. It is a safety device of merit.

The gas regulator 17 may be of the type shown in Fig. 4 of the U. S. Patent 485,386 dated November 1, 1892, and its function is to automatically reduce and maintain constant the pressure of gas 50 for delivery to the burners or the consuming appliances, regardless of demand or rate of flow. The gas regulator 17 may be of any suitable and desirable conventional or standard construction. The pressure of the gas between the regulator and 55 burners can be read on the pressure gauge or manometer 25.

The many safety features of the apparatus will now be described. At the top of the safety trap 13, there is a line L which joins with the lines K, 60 U and W. In the line L is valve 19. This valve is normally closed and is placed in the line so that pressure can be equalized on both sides of the unbalanced valve within the safety trap 13, should it close as a safety measure. Connecting 65 the lines H and A is the line F in which there is check valve 11, which may be of any suitable and standard positive seating type, but which preferably is of the construction disclosed in applicants' copending application, Serial No. 70 517,337, filed Feb. 20, 1931. This valve is set against the pressure of the liquid in the storage tank so that the liquid in the line F tends to keep the check valve closed under all normal operating conditions. However, should the valves 14, 75

13, 22, 17 or 23 in the discharge lines from the heat exchange unit P, be closed and continue to stay closed, and the heating medium be left circulating in the heat exchange unit P, the tendency would be to increase the pressure of the gas in the heat exchange unit pipes to above that in the storage tank, even though no more liquid were admitted by valve 4. In this case, the back pressure thus produced would cause the valve 11 to open, thus completing a direct communication through line F and the check valve to the storage tank. This check valve 11, therefore, provides an escape for high pressure liquid or gas from the vaporizing device preventing the pressure therein from rising substantially above the storage tank pressure and greatly diminishing the possibility of a rupture of any of the appliances incorporated therein. By opening the valve 9, any liquid in the trap 13 can be passed from the gas to the liquid carrying portion of the system. Other safety appliances will be seen at the top of the line T where a pop valve 26 is set to blow off when excessive pressure is built up between the regulator 17 and consuming points. The lead from this pop valve is through the line M to the vent pipe M2 and away from the building housing the apparatus. In the end of the heat exchange unit through which the gas passes last, is the relief valve 29, set so that when excessive pressure is built up in the apparatus, relief may be had. The lead from this safety valve 29 is through the line N to the vent outside of the building housing the apparatus. Besides the above mentioned safety features are the automatic expansion valve 4, the gas regulator 17, and the pressure gauge or manometer 25, all of which have been described previously. There is also the safety feature incorporated in the pressure gauge in the line A, from which pressure can be noted.

Through the control valve 4, liquid gas is automatically fed to the heat exchange unit P where it is converted into a true gas and by means of the regulator 17, this gas is reduced to the proper pressure for delivery and use. If, for any reason, the two above automatic appliances 4 or 17 cease to function, either or both, can be removed from the apparatus and the apparatus can be operated under manual control. After closing valves 1, 2, 20 and 21, (valve 10 is closed when liquid gas is being fed by automatic reducing valve 4), the expansion valve 4 can be removed as a unit from the apparatus after the three couplings supporting it have been undone. Thereafter, by opening the valve 1, liquid gas can be fed to the apparatus and the amount controlled by the valves 1 or 10. If, for any reason, the automatic gas regulator 17 ceases to function properly, gas can be fed directly from the heat exchanger P after the valves 22 and 23 in the line G have been closed. The manual control in this case is through the valve 18 in the line U. The pressure to which the gas is reduced and at which it is being fed to the burners can be read on the pressure gauge or manometer 25. From the above, it will be seen that the apparatus is automatically controlled throughout, but can be operated by a manual control if, for any reason, any of the automatic controls do not operate properly.

Attention is called to the fact that all of the system leading to the heat exchanger P is for liquid gas, while that leading from P is for the true gas after it has passed through the heat exchanger unit P. Each line leading from S may include a gas regulator so that any number of burners or appliances can be supplied at differ-

ent gas pressures providing the regulator for each line is set at the desired pressure, which must always be lower than the outlet pressure from 17. This is desirable because it is sometimes advisable to deliver to different points of gas use at different gas pressures. 5

If desired, an automatic shut-off valve 50, which may be of the type disclosed in U. S. Patent No. 1,678,202 dated July 24, 1928 preferably of the single seated unbalanced valve type, may be 10 mounted in the line J posterior to the thermostatic control 15, or at any suitable point, preferably just ahead of the vapor regulator 17. This valve, which may be of any suitable and desirable conventional or standard construction, may be wired into the motor control circuit of an air-gas plant, so that when the plant is shut down, the single seated unbalanced valve 50 is closed by means of the gas pressure, assisted by a spring, and is held closed by the spring and the 20 unbalanced pressure. This eliminates slight seepage of gas from the vaporizer through the outlet vapor regulator 17 to the proportioning machine for the air and gas or point of use, with consequent loss of vapor and possibility of creation of 25 a fire or explosion hazard.

From the foregoing it is believed that the construction, operation and advantages of our invention may be readily understood by those skilled in the art, and we are aware that changes may be 30 made in the details disclosed, without departing from the spirit of the invention, as expressed in the claims.

What we claim and desire to secure by Letters Patent is: 35

1. In an apparatus of the character described, a vaporizer for liquefied gas, an inlet conduit for conducting liquefied gas to said vaporizer, an outlet conduit for conducting the vaporized gas from the vaporizer, automatically operating 40 means interposed in the last mentioned conduit for reducing the pressure of said vapor and maintaining the same substantially constant, means interposed in the inlet conduit for automatically controlling the pressure of the liquefied gas fed to the vaporizer, means associated 45 with the vaporizer for passing a heating medium through the latter in indirect heat exchange with the liquefied gas flowing through the vaporizer, and thermostatic control means 50 associated with said outlet conduit and the heating medium means for regulating the volume of the heating medium fed through the vaporizer.

2. In an apparatus of the character described, a vaporizer of the heat exchange type, a conduit 55 for feeding liquefied gas into said vaporizer, a regulator interposed in said conduit for automatically controlling the pressure of the liquefied gas flowing to the vaporizer, and a by-pass pipe associated with the conduit and provided 60 with an automatic check valve for by-passing liquid reversely around said regulator, whereby flow in the reverse direction can occur if the vaporizer pressure becomes higher than the pressure of the source of the liquefied gas. 65

3. In an apparatus for vaporizing liquefied gas, a vaporizer, an inlet conduit for conducting liquefied gas to said vaporizer, an outlet conduit for conducting vaporized gas from said vaporizer, means interposed in the last mentioned conduit 70 for controlling the pressure of said vaporized gas, means interposed in the inlet conduit for controlling the pressure of the liquefied gas fed to the vaporizer, means for supplying heat to said vaporizer, and vaporizer control means associated 75

- with said heat-supplying means and said cutlet conduit for controlling the rate of vaporization in said vaporizer.
4. In an apparatus for vaporizing liquefied gas, 5 a vaporizer, an inlet conduit for conducting liquefied gas to said vaporizer, an outlet conduit for conducting the vaporized gas from the vaporizer, automatically operating means interposed in the last mentioned conduit for reducing the pressure 10 of said vaporized gas and maintaining the same substantially constant, means interposed in the inlet conduit for controlling the pressure of the liquefied gas fed to the vaporizer, means for imparting heat to said vaporizer, and thermostatic 15 control means associated with said last named means and responsive to temperature conditions in the outlet conduit for maintaining the temperature in the vaporizer within a predetermined temperature range.
5. In a gas apparatus, the combination of a 20 source of liquid gas supply, a heat exchange chamber, a pipe for conducting liquid gas from said source of supply to said chamber, pressure reducing means interposed in said pipe, a conduit arranged anterior to said chamber leading from said pipe, to said source of liquid gas supply, a 25 check valve arranged in said conduit and exposed on opposite sides thereof directly to the

liquid gas pressure from said source of supply and to the normally relatively reduced gas pressure from said heat exchange chamber, whereby said check valve is normally held in closed position but is opened to afford relief for the gas when the pressure of the gas in the heat exchange chamber becomes greater than the liquid gas pressure at the source of supply.

6. In an apparatus of the character described, 10 a vaporizer, a conduit for feeding a liquefied gas to said vaporizer, a regulator interposed in said conduit for automatically controlling the pressure of the liquefied gas flowing to the vaporizer, a by-pass pipe associated with the conduit and provided with an automatic check valve for bypassing liquid reversely around said regulator, 15 whereby flow in the reverse direction can occur if the vaporizer pressure becomes higher than the pressure of the source of the liquefied gas, an outlet conduit for conducting vaporized gas 20 from the vaporizer, automatically operating means interposed in the last mentioned conduit for reducing the pressure of said vaporized gas and maintaining the same substantially constant, and means for imparting heat to said 25 vaporizer.
